UNITED STATES PATENT OFFICE

106,796

DESIGN FOR A NAPPY OR SIMILAR ARTICLE

Curtis B. Ilgenfritz and Edwin E. Slick, Jr., Pittsburgh, Pa., assignors to United States Glass Company, Pittsburgh, Pa., a corporation of Pennsylvania

Application June 22, 1937, Serial No. 69,987

Term of patent 7 years

To all whom it may concern:

Be it known that we, Curtis B. Ilgenfritz and Edwin E. Slick, Jr., citizens of the United States, residing at Pittsburgh, county of Allegheny, in the State of Pennsylvania, have invented a new, original, and ornamental Design for a Nappy or Similar Article, of which the following is a specification, reference being had to the accompanying drawing, forming a part thereof, in which the figure is a perspective view of a nappy showing our design. The article in top plan is substantially circular in contour.

We claim:

The ornamental design for a nappy or similar article, substantially as shown and described.

EDWIN E. SLICK, JR.
CURTIS B. ILGENFRITZ.
